Specification for Design.

Patented July 15, 1919.

Application filed April 9, 1919. Serial No. 288,884. Term of patent 3½ years.

To all whom it may concern:

Be it known that I, FREDERICK E. GREENE, a citizen of the United States, residing at Mount Vernon, Westchester county, State of New York, have invented a new, original, and ornamental Design for a Plate for an Automobile-Lock or a Similar Article of Manufacture, of which the following is a specification, reference being had to the accompanying drawing, forming a part thereof.

In said drawing;
Figure 1 is a face view of a lock plate embodying my ornamental design.
Fig. 2 is an edge view of the same.
I claim:
The ornamental design for a plate for an automobile lock or a similar article of manufacture, substantially as shown.

FREDERICK E. GREENE.
